UNITED STATES PATENT OFFICE.

CARL GANTZHORN, OF NEW YORK, N. Y.

STOP-WATCH.

SPECIFICATION forming part of Letters Patent No. 234,768, dated November 23, 1880.

Application filed April 12, 1880. (No model.)

To all whom it may concern:

Be it known that I, CARL GANTZHORN, of the city, county, and State of New York, have invented certain new and useful Improvements 5 in Stop-Watches, of which the following is a specification.

In the accompanying drawings, Figure 1 represents a top view, and Fig. 2 a vertical transverse section on line xx , Fig. 1, of my improved 10 stop-watch.

Similar letters of reference indicate corresponding parts.

The invention has reference to an improved construction of stop-watch for use in timing 15 races and for other purposes; and it consists of a transmitting gear-wheel, which is arranged to slide vertically to the arbor of the second-hand by the action of a forked spring-arm and beveled lever. Fixed spring-arms of the arbor of the second-hand bear on pins of the sliding gear-wheel on the same side of the pins, so as to engage the gear-wheel in raised as well as in lowered 20 position. When raised by the lever and forked spring-arm the gear-wheel intermeshes with an intermediate gear-wheel, to which the shifting mechanism is applied, and which gears with a third gear-wheel, carrying the arbor of the 25 quarter-second hand.

Referring to the drawings, A represents the 30 arbor of the second-hand, from which my improved timing attachment receives its motion.

To the upper end of the arbor A are keyed 35 two spring-arms, $a a$, which extend radially from the arbor A. Below the spring-arms is arranged a gear-wheel, B, which slides loosely on the arbor A when raised or lowered by the free forked end of a spring-arm, C, the opposite end of which is permanently attached to the top plate of the movement.

Upon a cross-pin of the slotted middle portion 40 of the spring-arm C acts the beveled or wedge-shaped end of a fulcrumed lever, D, which, when pushed to one side or to the other, raises or lowers the spring-arm, and thereby 45 raises or lowers the gear-wheel B.

The spring-arms $a a$ of the second-hand arbor bear on pins $b b$ of the gear-wheel A, both upon the same side of the pins. One spring-arm serves to carry the gear-wheel along, while 50 the other arm serves as a cushioning-spring when stopping the timing attachment for the

purpose of neutralizing the shock imparted by the sudden stoppage, as well as for preventing any retarding influence on the second-hand gear.

55

When the gear-wheel B is raised it is thrown into gear with a second or intermediate gear-wheel, B' , which again gears with a third wheel, B^2 , turning loosely on the arbor of the minute and hour hands, and carrying on a sleeve the 60 quarter-second hand. The moment therefore the lever D is pushed to one side the intermeshing set of gear-wheels are thrown into motion and the timing quarter-second hand is started. On pushing the lever back the gear-wheel on the arbor of the second-hand is thrown 65 out of gear and the timing-hand stopped. It is then returned to the starting-point by the well-known shifting mechanism, consisting of a fulcrumed lever, E, and heart-cam E', the 70 latter being applied to the arbor of the second or intermediate gear-wheel, B' . A curved spring-arm, C', with forked end, extends from the spring-arm C to the arbor of the intermediate gear-wheel, B' , and bears upon the same 75 when the timing attachment is not in motion, but is raised with the spring-arm C' by the lever, so as to exert no friction on the intermediate wheel, as soon as the gear-wheel of the second-hand arbor is thrown into gear with 80 the intermediate gear-wheel for starting the timing attachment.

I am aware that the heart-cam and shifting-lever, as well as the starting and stopping lever and spring-arm, are well-known devices in 85 stop-watches, and I do not claim the same.

The essential feature of my stop-watch is the driving of the timing mechanism from the arbor of the second-hand and the connection of the sliding gear-wheel having projecting 90 pins by spring-arms of the arbor bearing on the same side of the pins, so that the gear-wheel is always carried along by the arbor of the second-hand, but at the same time a remedy provided for the shocks caused by the 95 starting and stopping of the timing attachment.

Having thus described my invention, I claim as new and desire to secure by Letters Patent—

1. In a timing attachment for watches, the combination, with the arbor of the second-

100

hand, having fixed radial spring-arms, of a transmitting gear-wheel sliding on said arbor and being provided with upwardly-projecting pins upon which the spring-arms bear at the same side, as set forth.

2. In a timing attachment for watches, the combination of a fulcrumed lever and forked spring-arm with a transmitting gear-wheel sliding on the arbor of the second-hand, said gear-wheel being connected by pins with radial spring-arms of the arbor bearing on the same side of the pins, substantially as described.

3. In a timing attachment for watches, the combination of a vertically-sliding transmitting gear-wheel connected by pins with spring-arms of the arbor of the second-hand, said spring-arms bearing on the same side of the pins, with an intermediate gear-wheel and shifting mechanism, and with a third wheel, carrying

the timing quarter-second hand, all as shown and described.

4. In a timing attachment for watches, the combination of a vertically-sliding transmitting gear-wheel connected by pins with spring-arms of the arbor of the second-hand, and of an intermediate gear-wheel, to which the shifting mechanism is applied, with a spring arm having two forked ends, one of which engages the lower part of the transmitting and the other the top part of the intermediate gear-wheel, substantially as specified. 25 30

In testimony that I claim the foregoing as my invention I have signed my name, in presence of two witnesses, this 5th day of April, 35 1880.

CARL GANTZHORN.
